UNITED STATES PATENT OFFICE.

CHARLES S. MOORE, OF GRAND RAPIDS, MICHIGAN.

WINDOW-FRAME.

SPECIFICATION forming part of Letters Patent No. 789,050, dated May 2, 1905.

Application filed August 13, 1904. Serial No. 220,658.

To all whom it may concern:

Be it known that I, CHARLES S. MOORE, a citizen of the United States, residing at Grand Rapids, in the county of Kent and State of Michigan, have invented certain new and useful Improvements in Window - Frame Constructions, of which the following is a specification.

This invention relates to an improved construction of window-frame; and the primary object of the invention is to provide means admitting of ready removal of the sash from the frame without mutilation of the casement, as is commonly necessary in the ordinary construction of frame at present in use. In other words, a side of the frame is provided with a movable section of substantially the length of one of the sash, and this movable section is adapted to be so operated as to admit of a lateral movement of a sash when the latter is moved alongside of the movable section to facilitate the displacement of the sash from the frame. It being often desirable to entirely remove the sash from the window-frame for cleaning the window-panes thereof or for removal of objects through the window, it will be seen that it is essentially desirable that the above may be quickly done without going to the trouble which is usually incident to this operation at the present time.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a view, partially in elevation and partially broken away, showing the practical embodiment of my invention. Fig. 2 is a view similar to Fig. 1, the movable section of the frame being shown in the position assumed thereby in order to remove one of the sash. Fig. 3 is a view looking toward the inner face of the side of the frame provided with the movable section and bringing out

clearly the manner of attachment of the supporting-strips, which coöperate with the movable section in the use of the invention.

Corresponding and like parts are referred to in the following description and indicated in all the views of the drawings by the same reference characters.

The window - frame is designated 1 in the drawings and is of any suitable construction generally employed in building structures. The upper and lower sash 2 are movably mounted in the sides of the frames in the usual manner, parting-strips 3 being utilized in order to properly direct the vertical movement of the sash. The sides of the frame are indicated at 4, and one of said sides is cut away at a point between the upper and lower ends thereof for some distance, a distance substantially the length of one of the sash 2. The cut-away portion 5 is of a width about the same as the combined width of the upper and lower sash, and this portion 5 receives a movable section 6, which entirely closes the side of the frame at the cut-away portion described. The movable section 6 may be made of boarding or of any suitable material and is provided with a parting-strip 3, forming a continuation of one of the parting-strips of the adjacent side 4 of the window-frame. In other words, the section 6 forms a part of the window-frame structure, and when the sash 2 are in position under normal conditions of service the section 6 is hardly to be noticed

The essential feature of the invention resides in the peculiar form of the section 6 of the window-frame and in the special means for mounting said section thereon. Supporting-strips 7 are attached to the rear or inner face of the side 4 of the frame which is cut away at 5, and these strips 7 are vertically disposed and located upon opposite sides of the cut-away portion 5, as shown most clearly in Fig. 3 of the drawings. The strips 7 are provided with inclined slots 8, continuations of which are formed in the side 4 of the frame upon opposite portions of the cut-away part thereof. The slots 8 extend rearwardly or horizontally for a short distance at their upper ends, as shown at 9, and two of these slots 8 are preferably provided at each side of the

movable section 6 in order to substantially and rigidly hold said section in supported relation relative to the strips 7. Projections 10 extend from opposite edge portions of the section 6, and these projections are received by the inclined slots 8 before described. A projection 10 is provided for each slot 8, and the several projections mentioned are formed by extended ends of transverse bars 11 passing through openings extended laterally through the movable section 6. The projections 10 form the means for supporting the movable section in the frame, and since these projections are adapted to move longitudinally of the slots 8 it will be noted that the movable section 6 may be readily forced rearwardly away from the plane of the body of the adjacent side 4 of the window-frame 1, and such movement will admit of a lateral movement of a certain sash 2 of the window in order to displace the said sash from the frame. It is necessary, of course, that the sash 2, which is to be removed, be adjusted vertically in the frame 1, so that the frame of the sash will assume a position beside the movable section before any lateral pressure upon said sash will be effective in securing the displacement thereof.

Describing specifically the operation of removing a sash from the window-frame for any of the purposes before enlarged upon, the movable section 6 is pressed upwardly and necessarily rearwardly until the projections 10 reach a position received in the uppermost portions 9 of the slots 8. Since the portions 9 of the slots 8 are horizontally formed, the

projections 10 will readily rest within these portions of the slots and the movable section will thus be held in its rearmost position. The above having been accomplished, a sash or both sash may be operated, so as to dispose the same alongside the movable section, whereupon lateral pressure upon the sash will cause a side of the frame thereof to be received in the cut-away portion 5 of the side of the window-frame 1, after which the whole sash may be quickly pulled outwardly from the frame 1 and displaced in a manner which will be readily apparent.

Having thus described the invention, what is claimed as new is—

In window-frame construction, and in combination, a side of the frame provided with a cut-away portion of substantially the same length as one of the window-sash of the frame, vertical supporting-strips applied to the rear face of the cut-away side of the frame upon opposite sides of the cut-away portion thereof, a movable section normally occupying the cut-away portion of the side of the frame, and projections extended from the edges of the movable section, the side of the frame and the strips applied thereto being provided with inclined slots to receive the projections of the movable section, the upper portion of said slots being extended horizontally.

In testimony whereof I affix my signature in presence of two witnesses.

CHARLES S. MOORE. [L. s.]
